CLAIM

The ornamental design for a balloon squeezer deflation aid, as shown and described.

DESCRIPTION

FIG. 1 is a side elevation view showing my new design, the corresponding side elevation view being identical;

FIG. 2 is a top plan view thereof, the bottom plan view being a mirror image of the top plan view;

FIG. 3 is an end elevation view of my new invention, the corresponding end elevation view being identical; and,

FIG. 4 is a perspective view of my new design.
FIGS. 1, 2 and 4 are shown fragmented to indicate indeterminate length.
